UNITED STATES PATENT OFFICE.

CORNELIUS B. CORCORAN, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,171,026.

Specification of Letters Patent. Patented Feb. 8, 1916.

Application filed July 9, 1913. Serial No. 777,983.

To all whom it may concern:

Be it known that I, CORMELIUS B. CORCORAN, a citizen of the United States, residing in New York, in the county of New York and State of New York, have invented certain new and useful Improvements in Type-Writing Machines, of which the following is a specification.

This invention relates to improvements in the front paper-guiding fingers of typewriting machines.

The object of this invention is to prevent the yielding paper-guiding fingers from being unduly sprung away from the platen by a stiff card or envelop, or by a large number of work sheets.

Each paper-guiding finger usually carries a feed roll, which controls the work sheet after the latter passes beyond the bottom feed rolls, and it is an object of this invention to hold said front rolls firmly against the card, when it is desired to write near the edge of the same.

The guide fingers are usually attached to carriers, which are slidable and partly rotatable upon a rail. The carriers are yieldingly splined to the rail, to permit the paper-fingers to be easily lifted from the platen. In carrying out the present invention, the carriers may be temporarily locked against turning on said rail. This is preferably done by means of a bolt device, which is adjustable with the carrier along the rail but is incapable of turning thereon, and may be manipulated to lock the carrier against rotating, so that the guide finger and roll are positively held against the platen.

A spring is located between the latch and carrier which normally tends to unbolt said carrier. This spring however, is not sufficiently powerful to overcome the friction between the bolt and the carrier (when the latter is locked); but upon depressing the guide finger, the friction is relieved, and the spring withdraws the bolt or latch to free the guide finger.

Other features and advantages will hereinafter appear.

In the accompanying drawings, Figure 1 is a perspective front view of the present improvements applied to the platen and

platen frame of an Underwood typewriting machine. Fig. 2 shews the cross section of the platen, with the improvements. Fig. 3 is a part-sectional front elevation showing the paper-guiding finger locked against rising. Fig. 4 is a similar view, showing the parts in normal positions. Fig. 5 is a perspective view of a locking collar or mount. Fig. 6 is a cross section showing the right-hand paper-finger bracket or mount pressed rearwardly and locked, (the paper-finger being of course pressed down toward the platen). At this figure, the yielding spline 11 is shown forced out of the groove in the rod 10. Fig. 7 is a similar view showing the locking mount partly in section. Fig. 8 is a similar view to Fig. 6, but showing the parts in normal positions, the paper-finger mount being unlocked.

The usual platen 1 is mounted between the platen frame ends 2, which are held together at the rear of the platen by a paper table 3. The work sheet 4 is fed around said platen with the aid of the usual bottom feed rolls 5, assisted by front or auxiliary feed rolls 6 on spring-metal guide fingers 7. Each guide finger 7 is held in position at the front of the platen 1 by an arm 8, extending from a carrier 9, which is mounted slidably and rotatably upon a rail 10, extending along the rear of the platen and connecting the platen frame ends 2. Either carrier 9 may be rocked by lifting the arm 8, to withdraw said guide finger and roll from the platen, and then shifted. The carrier 9 is provided with a long detent roll or spline pin 11, which is forced to a seat in a longitudinal groove 12 in the rail 10, by means of a spring 13, to yieldingly hold the front roll 6 against the platen as shown in Fig. 2.

According to the present invention, the guide finger may be locked against rising by a locking pin or bolt 14. This locking pin is mounted in a collar or mount 15, which is splined to the rail 10, with a screw 16, engaging groove 12, so that said collar may be shiftable along said rail, but not rotated. Normally the locking pin 14 is a trifle behind front edge 17 of the carrier 9; but if the arm 8 is forcibly depressed the carrier will be rocked back sufficiently to allow the

locking pin 14 to be projected in front of said carrier, to lock the latter against rotation.

The collar 15 is loosely connected to the 5 carrier 9 to shift therewith, by means of a finger 18 (Figs. 3, 4), the end of which is bent over to form a hook to hold said collar.

A releasing spring 19 is placed between the collar and the carrier. When the friction 10 between the carrier and the locking pin is relieved by depressing the arm 8, this spring will withdraw the locking pin.

Variations may be resorted to within the scope of the invention, and portions of the 15 improvements may be used without others.

Having thus described my invention, I claim:

1. In a typewriting machine, the combination of a platen mounted in a platen frame, 20 a rail supported in parallelism with said platen, a carrier mounted on said rail, a guide finger attached to the carrier, a roll mounted on said guide finger, a shiftable member splined to the rail, and a carrier locking pin on said member lying behind 25 the front edge of the carrier when the feed roll bears normally against the platen.

2. In a typewriting machine, the combination of a platen mounted in a platen frame, 30 a rail supported in parallelism with said platen, a carrier slideable and rotatable upon said rail, a guide finger attached to said carrier, a feed roll mounted in said guide finger, locking means for said carrier to 35 prevent said guide finger and feed roll from rising from the surface of the platen, said locking means held frictionally in an operative position, and means acting to render said locking means inoperative upon de- 40 pressing the guide finger.

3. In a typewriting machine, the combination of a platen mounted in a platen frame, a rail supported parallel to said platen, a carrier mounted to slide upon said rail, a 45 groove in said rail, means on said carrier adapted to engage said groove to yieldingly hold the carrier against rotation, a guide finger attached to the carrier, a roll mounted on said guide finger, engaging means on said rail, and means on said carrier adapted to 50 coöperate with said engaging means, whereby the carrier and the finger held thereby may be held rigidly against rotation.

4. In a typewriting machine, the combination of a platen mounted in a platen frame, 55 a rail supported in said frame parallel with said platen, said rail having a groove therein, a carrier slideable along said rail and having means for yieldably engaging said 60 groove, a guide finger on said carrier, and means on the rail engaging said groove for positively locking said carrier against rotation.

5. In a typewriting machine, the combination of a platen frame, a platen mounted

therein, a round rail supported in said frame parallel with the platen, a groove in said rail extending lengthwise thereof, carriers mounted on said rail, spring-held members mounted on said carriers and adapted for 70 engagement with the groove of said rail, paper-holding fingers mounted on the ends of said carriers and adapted to press the paper toward the platen when the spring-held member is in engagement with the 75 groove of the rail, and means on said rail engaging said groove for positively locking said carrier against rotation.

6. In a typewriting machine, the combination of a platen frame, a platen mounted 80 therein, a grooved rod secured to said frame parallel with the platen and having its groove on the under side, carriers mounted to slide upon and turn about said rod, said carriers being provided with detent rolls 85 spring pressed into the groove and lying parallel with the rod, a locking pin rigid with said rod, and means on said carrier with which said pin may engage, said means and pin being so arranged that engagement 90 occurs only when the carrier and the finger are depressed.

7. In a typewriting machine, the combination of a platen frame, a platen mounted 95 therein, a rod mounted upon said frame and extending parallel with the platen, means upon the circumference of said rod for engagement with a yielding locking means, carriers mounted to turn about said rod, paper-engaging fingers on said carriers, 100 yielding locking means on said carriers adapted to engage with the means aforesaid on the circumference of said rod, whereby said carriers and fingers are yieldingly held in paper pressing relation to the platen but 105 may turn away from the platen, and means on said rail engaging said groove for positively locking said carrier against rotation.

8. In a typewriting machine, in combination, a platen frame, a platen therein, a 110 rod mounted on said frame parallel to said platen, said rod having on its circumference a place for engagement with a yielding locking means, a carrier on said rod, a paper engaging finger on said carrier, a yielding 115 locking means for engagement with the said place on said rod, a pin mounted on the rod in fixed angular relation thereto but slideable lengthwise thereon, said pin being so located with reference to the carrier as to be a trifle 120 behind its front edge normally.

9. In a typewriting machine having a platen and a rail parallel therewith, a guide-finger slidably and rotatably mounted on said rail with spring means pressing it toward said platen, and a self-releasing lock also mounted on said rail and capable of holding said guide-finger in operative position.

10. In a typewriting machine having a 130

platen and a rail parallel therewith, a carrier with a guide-finger and feed-roll slidably and rotatably mounted on said rail, spring means pressing said guide-finger and feed-roll toward said platen, and a self-releasing lock also mounted on said rail and coöperating with said carrier to hold said

guide-finger and feed-roll in operative position.
